UNITED STATES PATENT OFFICE

2,630,538

ELECTRIC LAMP STAND

Erwin Frank Brede, Detroit, Mich.

Application January 27, 1950, Serial No. 140,901

2 Claims. (CL. 307—147)

1

The object of this invention is to provide a portable electric lamp stand offering a system of dual control of the lamp at the two points separated by the length of the lamp cord and integral with the unit construction of the portable lamp.

The purpose of the invention is to effect more extensive visibility by means of dual control of a portable electric lamp stand to prevent fumbling and stumbling through the dark to control the lamp. One further purpose is to provide such a lamp which can be carried as a complete unit to any place, where a conventional electric outlet receptacle is available, to at once provide use of the system.

Heretofore, and prior to December 1891 an electric circuit has been used which comprises two companion wires connected between two sets of contact points, respectively, of two three-point switches with their blades connected in series with the control line wire so that the circuit may be opened or closed by either of the two switches. The use of the circuit is found in stationary installations and installations composed of several individual parts which can be connected or disconnected by electric wires at will and the terminal wires of the system connected to the power mains. But, obviously, such systems are not readily or conveniently portable.

My invention incorporates such an electric circuit described in the preceding paragraph but makes it an integral part of the structure of the portable dual control electric lamp stand of unit construction.

It is well to remember that for safety, as with any lamp cord, the cord should always be kept out of the path of walk of any individual.

Referring to the drawings:

Figure 1 is a side elevation of such a lamp except it does not show the plug-switch which, however, is shown in Figure 2. Any ordinary lamp stand may be used for the application of the invention.

Figure 2 is a plan view of the plug-switch, assembled, which plugs into the electric service outlet and provides a means of on and off control of the lamp at that point regardless of the position of the switch on the lamp base.

Figure 3 is an end view of the prong end of the plug-switch, assembled.

Figure 4 is a longitudinal sectional view, having portions thereof in elevation, of the plug-switch.

Figure 5 is an end view of the external end-bushing of the housing of the plug-switch.

Figure 6 is an end view of the internal parti-

2

tion made of plastic insulator which, when the plug-switch is assembled, carries the two terminal prongs which plug into the receptacle of the electric service.

5 Figure 7 is a side elevation of the internal partition.

Figure 8 is an electric circuit diagram of the electric parts and connections of the dual control electric lamp stand including plug-switch, complete.

Referring to the drawings for a detailed description; in Figure 1 the lamp shade is 1, and 2 is a customary keyless electric socket mounted on top of the center post 4; 3 is one of the four brackets, fastened to the four sides of the center post 4, which support the lamp shade 1; 5 is a customary switch knob fastened to the shaft of a rotary single pole double throw snap switch mounted in the base piece 7 of the lamp stand; 6 is two nuts on the switch bushing which hold the switch in place; 8 is a thin flat plate used to conceal the insulation and recess into which the switch is inserted and is held in place by four small screws; 9 and 10 are two of four small blocks fastened to the base piece 7 by glue and screws which provide the feet for the base; 11, which also appears in Figures 2, 3, and 4, is a three conductor lamp cord completing the electric circuit from the lamp, Figure 1, to the plug-switch, Figure 2.

30 Referring to Figure 2, the knob 12 is fastened by a set screw to the shaft of a rotary single pole double throw snap switch 22 in Figure 4. Two lock nuts 13, also shown in Figure 4, hold this snap switch in place. 14, also shown in Figure 4, is the cylindrical part of the housing. 15 and 16 are two of three small machine screws which are spaced 90° apart and secure the internal partition 19, shown in Figures 4 and 7, to housing 14. These three screws are also shown in Figure 3.

35 The terminal prongs 17 and 18, also shown in Figure 4, are fastened to the internal partition 19 and are the means of plugging into the electric service outlet.

40 Referring to Figure 4, the hole 20 in the cylindrical housing 14 admits the three-conductor lamp cord 11 into the plug-switch. 21 is the external end-bushing, also shown in Figure 5, which is cemented to the rest of the housing but can be fastened thereto in any customary manner. 22 is the rotary single pole double throw snap switch of the plug-switch and 23 is the shaft of this switch.

45 Referring to Figure 5, the small key-seat 25 holds the small key projecting from the periphery

of the snap switch secured by lock nuts 13 in Figure 4 when the plug-switch is assembled.

Referring to Figure 6, 26 is one of three tapped holes, spaced 90° apart, to receive the three machine screws designated by 15 and 16, Figures 2 and 3. The hole 27 is one of the two holes which clear the screw ends of the binding screws on the terminal prongs 17 and 18, Figures 2 and 4. The hole 28 is one of the two holes which receive the two self-tapping machine screws that secure the terminal prongs to the internal partition 19, and 29 is a slot in the internal partition to receive the three conductors of the three conductor lamp cord for connection to the plug-switch.

Referring to Figure 8, 30 is the blade of the rotary single pole double throw snap switch in the plug-switch and 31 is the blade of the rotary single pole double throw snap switch in the lamp base.

Although this invention is described herein with relation to a specific lamp stand its application is not confined to any specific lamp stand and it is intended to cover any type of lamp stand to which it is applied to effect the improvements explained herein and coming within the scope of the following claims but it is not intended to include any already existing patent on other improvement embodied in a lamp stand.

I claim:

1. In an electric lamp stand a novel improvement effected by combining in a single portable unit: the lamp stand, a single pole double throw rotary snap switch mounted in the lamp stand, a three conductor lamp cord, a switch-plug embodying a single pole double throw rotary snap switch combined with two terminal prongs; all so integrated that one end of the three conductor lamp cord is permanently connected in such manner that one of the conductors thereof is permanently connected to one of the two terminals of the lamp socket, the other two conductors thereof are permanently connected to the set of two contact points, respectively, of the switch

mounted in the lamp stand, and the switch blade of this switch is permanently connected to the other socket terminal, the other end of the three conductor lamp cord is permanently connected in such manner that the first conductor is permanently connected to one of the two terminal prongs embodied in the switch-plug (thus one side of the circuit is permanently closed by this first conductor), the other two conductors are 10 permanently connected to the set of two contact points, respectively, of the switch embodied in the switch-plug, and the switch blade of this switch is permanently connected to the other terminal prong (thus alternate switching to either of these two remaining wires is effected by either of the two switches to open or close the circuit at either of the two switches).

2. In a portable electric lamp stand comprised in a complete unit, the combination in a single primary unit of a single pole double throw rotary snap switch, integral with two terminal prongs thereby forming a switch-plug of unit construction embodying in its structure one end of a three conductor lamp cord in such manner that: one of the conductors thereof is permanently connected to one of the two terminal prongs; the other terminal prong is permanently connected to the blade of the single pole double throw switch; the second conductor is permanently connected to one of the two contact points of the switch; and the third conductor is permanently connected to the other contact point of the switch.

ERWIN FRANK BREDE.
